REVOLVING SEWING STAND OR SIMILAR ARTICLE

Fred A. Willner, 9518 E. Broadway,
Spokane, Wash. 99206

Filed July 16, 1969, Ser. No. 18,234

Term of patent 14 years

Int. Cl. D6—99

U.S. Cl. D3—19

FIG. 2

FIG. 1 is a top perspective view of a revolving sewing stand or similar article, showing my new design; and

FIG. 2 is a bottom perspective view of the side opposite that shown in FIG. 1.

I claim:

The ornamental design for a revolving sewing stand or similar article, substantially as shown.
